Primary Examiner — Patricia A Palasik(74) *Attorney, Agent, or Firm* — Schwegman Lundberg & Woessner, P.A.(57) **CLAIM**

The ornamental design for an industrial robot, as shown and described.

DESCRIPTION

FIG. 1 is a front, top, and right side perspective view of our design for an industrial robot;

FIG. 2 is a front view thereof;

FIG. 3 is a rear view thereof;

FIG. 4 is a top plan view thereof;

FIG. 5 is a bottom plan view thereof;

FIG. 6 is a right side view thereof; and,

FIG. 7 is a left side view thereof.

The broken lines illustrate portions of the industrial robot that form no part of the claimed design.
